Primary Examiner—Gary D. Watson*Assistant Examiner*—Susan Bennett Hattan(74) *Attorney, Agent, or Firm*—Klarquist Sparkman, LLP(57) **CLAIM**

I claim the ornamental design for a valve for dispensing spout, as shown and described.

DESCRIPTION

FIG. 1 is a perspective view of a valve for dispensing spout, according to my new design, as viewed from the top thereof.

FIG. 2 is a perspective view of the valve of FIG. 1, as viewed from the bottom thereof.

FIG. 3 is a top plan view of the valve of FIG. 1.

FIG. 4 is a cross-sectional view taken along line 4—4 of FIG. 3.

FIG. 5 is a bottom plan view of the valve of FIG. 1.

FIG. 6 is a side elevational view of the valve of FIG. 1.

FIG. 7 is a side elevational view of the valve rotated 90 degrees from the position shown in FIG. 6; and,

FIG. 8 is an elevational view of the side of valve opposite of that shown in FIG. 7.
